UNITED STATES PATENT OFFICE.

WILLIAM JAMES GEORGESON, OF ONEONTA, NEW YORK.

MOTOR-DRIVEN GEARING.

1,342,262.

Specification of Letters Patent. Patented June 1, 1920.

Application filed July 29, 1918. Serial No. 247,199.

To all whom it may concern:

Be it known that I, WILLIAM JAMES GEORGESON, a citizen of Greece, and resident of Oneonta, in the county of Otsego and 5 State of New York, have invented certain new and useful Improvements in Motor-Driven Gearing, of which the following is a specification.

This invention relates to the class of agitators, and more particularly to drink mixers designed to be used in connection with soda fountains, or the like, for preparing 10 various mixed drinks.

The primary object of the invention is to 15 provide a novel device of the above character in the form of a double drink mixer whereby a plurality of drinks may be mixed at the same time, the parts being constructed in a novel manner so as to facilitate the application and removal of the receptacle or 20 glass containing the drink, and for simultaneously driving two agitators, as will be hereinafter more fully set forth.

With the above and other objects in view, 25 as will appear as the description proceeds, the invention comprises the various novel features of construction and arrangement of parts which will be more fully described herein and set forth with particularity in 30 the claims appended hereto.

Reference is had to the accompanying drawings forming a part of this application, in which like reference characters indicate the corresponding parts throughout the several views, in which—

Figure 1 is a front elevation of one form of the improved double drink mixer constructed in accordance with my invention,

Fig. 2 is a plan view thereof,

Fig. 3 is a vertical cross section taken through one of the containers and showing the mounting of the dasher,

Fig. 4 is a horizontal cross sectional view taken on the line 4—4 of Fig. 3,

Fig. 5 is a disassembled perspective view of a dasher shaft and its mounting,

Fig. 6 is a vertical sectional view showing a modified form of the device, in which the agitators operate through the bottom of the 50 containers instead of from the top thereof, and

Fig. 7 is a plan view of the device shown in Fig. 6 with the containers removed.

Referring to the drawings in detail, and 55 more particularly to the form of the inven-

tion illustrated in Figs. 1 to 5 inclusive, my improved double drink mixer is shown as comprising a base 10 having arranged thereon a permanent standard 11 disposed intermediately between the ends of the base 60 10 and carrying a motor 12 arranged in a suitable casing provided with a handle 13 for conveying the device from place to place and having flexible connections 14 leading to the motor from a suitable source of energy so that the motor will be electrically operated.

Rigidly supported in a horizontal position by the standard 11 is a pair of spaced parallel plates 15, the same accommodating the 70 shaft 16 of the motor which has a gear 17 mounted thereon between the plates, the plates being secured in fixed relation as shown at 18. The plates are positioned in spaced relation below the motor casing and 75 immediately above the glasses or other containers indicated at 19, as designed to be placed upon the base 10 in the act of mixing the various drinks.

The dashers for agitating the drinks are 80 indicated at 20, the same being in the form of vertical shafts carrying suitable agitating projections 21 on their lower ends designed to enter the glasses or containers 19, which are held by suitable clamping members or arms 22 of a resilient nature carried by uprights 23 arranged upon the base for this purpose. Each dasher staff or shaft 20 is provided with an enlarged squared portion 24 near its upper end, received within a 90 sleeve 25 having a square bore 26 and an enlargement 27 provided with a peripheral notch 28 for the purpose of detachably fixing pinions or gears 29 thereto between the respective plates 15. Suitable keys 30 are 95 provided for connecting the pinions 29 with the sleeve 25, although it is obvious that any other suitable detachable fixing means may be employed if desired. The pinions 29 are also disposed in mesh with the pinion or 100 gear 17, so as to be simultaneously rotated for rotating both agitating or dasher shafts for the purpose of mixing the various drinks, a plurality at a time. To permit the placing and removal of the container or 105 glass, the shafts 20 are made vertically slideable in the squared portions of the sleeves 25 and are provided with operating knobs or handles 31 on their upper ends capable of detachment and forming shoulders as indi-

cated at 32 designed to engage the topmost of the plates 15 as a means of support in connection with the shoulder produced by the reduced circular lower portion of the shaft 5 20, with respect to the squared portion 24.

In the form of the invention shown in Figs. 6 and 7 a base 33 is provided adapted to support the motor contained in a casing 34, suitable electrical connecting wires 35 10 being arranged to carry the current to the motor, while as in the previous form, suitable means are provided for closing the circuits when the device is to be used. The motor shaft is indicated at 36, extending 15 upwardly from the motor, while the casing 34 is designed to support a pair of spaced plates 37, corresponding to the plates 15, in that they are held in spaced parallel relation and secured together, as shown at 38.

20 Arranged upon the shaft 36 is a gear or pinion 39 suitably fixed thereto and adapted to mesh with pinions or gears 40 removably mounted upon sleeves 41 journaled between the spaced plates, so that the pinions or 25 gears 40 will mesh with the pinion or gear 39. The plates are also provided with vertically aligned openings corresponding to the bores of the sleeves 41, so as to receive the squared lower ends of shafts 42, which 30 shafts have detachably secured to their upper ends containers or glasses 43, through which the shafts rotate in the form of dashers at the bottoms of the glasses, or containers, suitable agitating means 44 being provided on the upper ends of the shafts as shown. The base portions 45 of the containers are held from rotation by engagement with pins or stops 46, so that when 35 the motor is started and the containers are 40 applied by engaging the depending squared lower portions of the shafts 42 in the squared portions of the sleeves 41, both agitators will be rotated for stirring or mixing the ingredients of the drinks, in the usual 45 way of agitating, as it is thought will be readily understood.

From the foregoing description taken in connection with the accompanying drawings, it is thought that a clear and comprehensive understanding of the construction, operation, and advantages of my invention 50 may be had, and while I have shown and described the device as embodying a

specific structure, I desire that it be understood that such changes may be made in 55 said structure as do not depart from the spirit and scope of the invention as claimed.

Having thus described my invention, what I claim is new, and desire to secure by Letters Patent, is:

1. In combination a base, a motor casing supported thereon having a vertical shaft, a pair of spaced plates receiving said shaft, a gear fixed to said shaft and located between said plates, gears journaled between 65 the plates in mesh with the first mentioned gear and provided with polygonal bores, cylindrical shafts movable axially through the bores of the gears and provided with an enlarged polygonal upper terminal adapted 70 to snugly fit the polygonal bores of the gears to establish a driving connection therewith, the cylindrical body portions of the shaft being movable into the polygonal bores of the gears to permit rotation of the 75 latter independently of the shafts, and handle knobs carried by the upper terminals of the shafts limiting the downward movement of the latter through the gears.

2. In combination a base, a motor supported thereon provided with a drive gear, a pair of spaced bearing plates supported above the base and receiving the drive gear, sleeves provided with reduced terminals journaled in and confined between the plates 85 and provided with polygonal bores, demountable driven gears non-rotatably secured to the sleeves between the plates and permanently meshing with the drive gear, axially movable shafts mounted in the bores 90 of the driven gears having cylindrical body portions and enlarged polygonal terminals adapted to snugly fit the polygonal bores of the driven gears to establish a driving connection therewith, the shafts being movable to elevated position to dispose the cylindrical portions thereof within the polygonal bores to permit independent rotation 95 of the driven gears with relation to the shafts, and handle knobs carried by the upper terminals of the shafts for limiting the axial movement of the polygonal portions of the shafts through the sleeves.

In testimony whereof I affix my signature hereto.

WILLIAM JAMES GEORGESON.
